UNITED STATES PATENT OFFICE.

CHESTER J. RANDALL, OF NAUGATUCK, CONNECTICUT, ASSIGNOR TO THE GOODYEAR'S INDIA RUBBER GLOVE MANUFACTURING COMPANY, OF NAUGATUCK, CONNECTICUT, A CORPORATION OF CONNECTICUT.

STRIPPING MACHINE.

Application filed December 7, 1922. Serial No. 605,375.

To all whom it may concern:

Be it known that I, CHESTER J. RANDALL, a citizen of the United States, residing at Naugatuck, county of New Haven, State of Connecticut, have invented certain new and useful Improvements in Stripping Machines, of which the following is a full, clear, and exact description.

This invention relates to a stripping machine, more particularly, to a machine for removing footwear articles such as boots from the forms on which they are built and cured.

In the making of vulcanized footwear articles such as boots they are usually built up by superposing the pieces on a form, the operator uniting the parts by rolling with a small hand roll, the article being then cured in open heat. If this rolling operation is not carefully performed small air bubbles are likely to remain between the layers of material, which when the article is cured form blisters. In addition, if the rolling has not been carefully performed the union between the various layers is frequently imperfect and as a result the parts tend to separate in use. To obviate these defects a method of curing known as the differential cure has gone into extensive use in recent years, this method employing a differential pressure on the exterior and interior of the article during the curing operation, the pressure being ordinarily obtained by exhausting the air from the interior of the article. By this method a very good union is secured between the parts and the formation of blisters is practically prevented. By reason of the pressure however the interior surface of the article is driven into very intimate contact with the surface of the last or tree, with the result that the article is difficult to remove from the form after curing, and considerable time and hand labor are required for the operation. In addition, owing to the rough handling a percentage of the articles are damaged and must be scrapped or sold as seconds.

An object of my invention is to reduce the time and labor required in removing vulcanized articles from the forms on which they are cured.

Another object is to reduce the number of seconds formed in removing such articles.

Another object is to provide an automatic machine for stripping vulcanizable articles such as footwear from the forms on which they are cured. 55

Still another object is to provide a machine for successively removing the sections of sectional forms on which footwear articles such as boots are cured. 60

For a detailed disclosure of the invention, reference is had to the accompanying specification and drawings, in which latter:—

Figure 1 is a plan view of the machine; 65

Figure 1^a is a detail of the boot clamp slides;

Figure 2 is a plan, partly in section, of the lower portion of the machine shown in Fig. 1; 70

Figure 3 is a front elevation of the upper right-hand part of the machine shown in Fig. 1;

Figure 4 is a side elevation partly in section of that portion of the machine shown in Fig. 3; 75

Figure 5 is a side elevation of the lower part of that portion of the machine shown in Figs. 3 and 4;

Figure 6 is a side elevation of that part 80 of the machine for removing the toe sections of sectional boot trees;

Figure 7 is a section of one of the pressure fluid operating cylinders;

Figure 8 is a side elevation of a control- 85 ling valve;

Figure 9 is a vertical section on the lines 9—9 of Fig. 8, and showing one position of the valve;

Figure 10 is a horizontal section on the 90 lines 10—10 of Fig. 9 but showing the valve in a different position;

Figure 11 is a transverse section through a boot clamp; and

Figure 12 is a perspective of a boot leg 95 closure.

Referring to the drawings, the numeral 1 designates a base which is supported by the legs 2. Secured to the base in spaced relation are a pair of tubular uprights 100 or guides 3 and 4 to the top of which is secured an operating cylinder 5. The uprights are also utilized to supply and exhaust pressure fluid from the cylinder, the upright 3 communicating by a passageway 105 6 with one side of the piston 7 of the cylinder.

der, while the upright 4 communicates by a passageway 8 with the opposite side of the piston. Secured to the piston 7 is a piston rod 9 carrying at its lower end a clamping 5 jaw 10 for engaging the projecting end of a boot tree, the jaw 10 sliding on the uprights 3 and 4 by means of the bearings 11. The lower face of the jaw is provided with a concave recess 12 in which is secured a 10 facing 13 of leather or any other suitable material for frictionally engaging the projecting end of the boot tree. Pivots connected to each side of the clamping jaw 10 are links 14, the lower ends of which are 15 pivotally connected to levers 15 fulcrumed on brackets 16 rigidly connected to the uprights 3 and 4. The opposite ends of levers 15 are connected by links 17 to a lower tree clamping jaw 18 which is similar to the upper 20 per jaw 10 and slides on the uprights 3 and 4 by means of bearings 19. The jaw 18 is provided with a concave recess 12 and facing 13 in all respects similar to those carried by the upper jaw.

25 It will be seen that upon a downward movement of the piston 7, the clamping jaw 10 moves downwardly while by means of the links 14, levers 15 and links 17, the lower clamping jaw 18 is moved upwardly, and 30 upon an upward movement of the piston 7, the movements of the jaws are reversed. The piston 7 is actuated in the following manner. Connected to the lower ends of the uprights 3 and 4 are supply pipes 20 and 21 35 leading into the casing of valve 22 disposed at the side of the machine. By reference to Figures 8 to 10 it will be seen that the valve casing is provided with an interior chamber 23 to which leads an inlet 24 in communication with the air supply pipe 25 leading from a main 25'. The respective pipes 20 and 21 lead into the valve chamber 23 through passageways or inlets 26 and 27, and over these inlets is disposed a rotatable valve 40 disc 28 having a port 29 therein, which in 45 the position shown in Figures 8 and 9 is in registry with the passageway 27, thereby allowing air to pass from the main into the cylinder 5 on the lower side of piston 7.

50 The valve disc 28 is also provided on its lower side with a curved groove 30, which in the position shown in Figures 8 and 9, establishes communication between the passageway 26 and an exhaust-opening 31, hence 55 it will be seen that at this time the air on the upper side of piston 7 may exhaust through the opening 31. In the position shown in Figures 8 and 9 further anti-clockwise movement of the valve disc 28 is prevented by the engagement of the stop lug 32 against stop 33 on the valve casing. When the valve is turned in a clockwise direction to the position shown in Figure 10, the port 29 moves out of registry with the 60 passageway 27, while the segmental groove 65 30 opens up communication between said passageway and the exhaust outlet 31. At the same time the elongated port 34 in the valve disc 28 registers with the passageway 23 and allows air from the main to enter the 70 space above piston 7 of cylinder 5 thereby reversing the movement of piston 7 and the clamping jaws 10 and 18. The valve disc 28 is held in engagement with its seat by the coil spring 35 surrounding the lower portion of the valve stem 36, the latter at its lower end being flattened where engaging the corresponding groove 37 in the valve disc. Secured to the valve stem 36 is an operating lever 38 which is connected 80 by the link rod 39 with a foot lever 40 fulcrumed on the leg 2. The lever 40 is returned to its upper position, after actuation, by the coil spring 41 secured to the lever and to the base 1.

85 Mounted at the rear end of the base 1 is an upright bracket 42 which is connected by the brace rods 43 with the brackets 16 (Figs. 1 and 4). Extending rearwardly from the upper end of bracket 42 are rods 44 rigidly secured to the bracket and connected at their outer ends by a plate 45. A pipe section 46 extends loosely through the plate 45 and is provided at its outer end with a closure cap 47 (see Fig. 1), which cap also acts as a 90 stop to limit the movement of pipe 46 in one direction. Secured to the other end of the pipe 46 is a cross coupling 48, and mounted on the pipe between said coupling and the plate 45 is a coiled compression spring 49 100 which tends normally to keep the cap 47 in engagement with plate 45. A tapered boot tree engaging nozzle 50 is secured to the forward arm of the cross coupling 48 by a flexible joint 50', while short pipe sections 105 51 are secured to the lateral arms of the cross coupling, one of said pipe sections 51 being closed by the cap 52. Flanges 53 are mounted on the pipe sections 51 which flanges act as guides to prevent lateral movement when the pipe sections 51 move rearwardly on the guide plates 54. Each of these guide plates has rigidly secured thereto a pair of downwardly extending guide rods 55 passing freely through guide openings in a plate 56 secured to bracket 42. Mounted on each guide rod 55 between the plates 54 and 56 is a coiled compression spring 57, the pressure of which may be varied by means of the adjusting nut 58, the latter being held in position by a lock nut 59. It will be seen from the above construction that the entire assembly carried by the cross coupling 48 may be moved rearwardly 110 against the pressure of spring 49 and also down against the pressure of springs 57, while at the same time, the nozzle 50 may also be moved on the flexible joint 50', these adjustments being provided to take care of 115 variations in the size and positioning of the 120 125 130

article to be removed from a tree. Attached to the pipe section 51, which is opposite the closure 52, is a flexible pipe 60 leading to a spring closed valve 61 mounted on and in communication with the air pipe 25. The valve plunger 62 of the valve is operated by one end of the lever 63 pivotally connected to the valve casing, the opposite end of the lever being connected to a link 64 having a reduced lower portion 65. Secured to the end of the reduced lower portion is a head 66, and a coiled spring 67 is disposed on said reduced portion between the head 66 and a slidable washer 68 mounted on said reduced portion. A valve operating arm 69 is slid-able on the rod 64 and has one end rigidly connected to a valve operating rod 70 connected to the foot lever 40. It will be seen that by varying the position of the arm 69 on the rod 70 its time of engagement with the washer 68 will be varied to thereby vary the time of opening of the valve 61.

Projecting upwardly from the base 1 is a longitudinally extended member 71 having at its top the laterally extending guide flanges 72 forming a runway for the carriage 73, which latter is held in position by the plates 74 engaging the lower surfaces of the flanges 72. Projecting from the rear end of carriage 73 is a lug 75 in which is mounted a small detent roller 76 (Fig. 4), the purpose of which will be later explained. The carriage 73 is laterally cut away as shown at 77 in Figure 1^a to provide a slideway in which are mounted the laterally movable interengaging slides 78, each of which is provided with the anti-friction rollers 79. Projecting upwardly from each slide 78 is a projection 80 on which a boot clamping jaw 81 is pivotally mounted at 82. Each boot clamping jaw is provided with a cushion, the construction of which is shown in detail in Figure 11, these cushions being omitted from the showing in the remaining figures for the sake of clearness. Secured in each jaw 81 is a base 83 which may be made of wood, this base having a convex outer surface to which the cushions 84 encased in canvas or other coverings 85 may be secured. The cushions 84 may be made of sponge rubber or any other suitable material, and over the cushions a sheet 86 of rubber is preferably disposed. Any other suitable form of cushion for the boot clamps may be used. In order to prevent tilting of the jaws and their supporting slides 78 when pressure is applied, retaining plates 87 are disposed over the slides 78, these plates being secured to the carriage by bolts 88, and the plates 87 being cut away as shown at 89 in Figure 1 in order to allow for movement of the upstanding lugs 80. Bell crank levers 90 are pivotally mounted on each side of the carriage at 91, one end of each lever being connected by a link 92 to the lug 80

of a corresponding slide 78, while the opposite ends of the levers 90 are connected by the links 93 to a connecting block 94, which latter has pivotally mounted therein a link 95 connected at its opposite end to 70 a lever 96 fulcrumed at 97 on a bracket 98 carried by the base 1. The lower end of the lever 96 is connected by a link 99 to the piston rod 100 of a piston 101 movable in a cylinder 102 and secured below the base 1 75 (Figs. 5 and 7). The piston rod 100 is extended through the cylinder 102 and connected to a piston 103 in a small oil check cylinder 104 of usual construction. Leading into the cylinder 102 on opposite sides of the piston are the respective air supply pipes 105 and 106, which pipes at their opposite ends lead into the casing of a valve 107 similar in all respects to the valve 22. The operating lever 108 of valve 107 is connected 80 to the rod 70 previously described.

A detent 109 adapted to engage the detent roller 76, previously mentioned as carried by the carriage 73, is mounted on a lever 110 supported on the base 1, the opposite end 90 of the lever having pivotally connected thereto a threaded rod 111 passing freely through the base 1. Threaded on the rod 111 is a thumb nut 112 and between said nut and the base 1 a coiled spring 113 is disposed on rod 111. From this construction it will be seen that the detent 109 resiliently holds the carriage 73 against movement to the left as shown in Figure 4, hence when power is applied to the lever 96 by piston 101 the forward movement of the upper end of lever 96 first actuates the bell crank levers 90 to move the slides 78 toward each other, thereby clamping the jaws 81 on a boot disposed between them. As soon as the boot 105 is clamped further movement of the jaws in this direction is prevented and the continued forward movement of the upper end of lever 96 thereupon moves forward the carriage 73 and all associated parts against the resistance of detent 109. In order to prevent abrupt stoppage of the carriage on its return movement a bumper 114 is provided. This bumper is of angular shape as shown in Figure 4 and is slidably mounted on the 110 guide rods 115 secured to the member 71. The coiled springs 116 are disposed on the guide rods 115 between the heads of said rods and the bumper 114 and the latter is also provided with steady pins 117 movable 115 in recesses in the member 71.

The mechanism above described may be utilized to withdraw a boot from a boot tree of the type in which the toe and leg sections are permanently connected, but at 125 present, sectional boot trees having slidably connected toe and leg sections are largely used. In trees of this type the mechanism previously described withdraws only the leg section and in order to withdraw the toe 130

section, the following mechanism is provided. A rest 118 is provided for the lower or heel portion of the boot as shown in Figure 6, this rest being secured to the base 1. At the rear of the base a pair of supporting brackets 119 are secured, which are united at the top by the angled bearing bracket 120 in which is rotatably mounted a shaft 121 having rigidly secured thereto an angled arm 122, the forward end of which terminates approximately above the rest 118 and carries a pair of small flexing rollers 123 and 124 for a purpose to be later described. Also rigidly secured to the shaft 121 is the operating arm 125 connected by the link rod 126 to the foot lever 127, the latter being returned to inoperative position by the coiled spring 128. A stop 122' on the arm 122 is adapted to engage the bracket 120 to limit its movement in one direction. A boot leg closure 129 of the shape shown in Figure 12 is carried by a pipe 130, which latter has a discharge opening leading through the closure, the pipe 130 being connected to the spring closed valve 131, having the operating plunger 132. The valve communicates with and is supported by an air supply pipe 133 leading into the tank 134 disposed below the base 1, said tank being in communication by the pipe 135 with the supply main 25'. A bracket 136 is supported on the valve 131 and pivoted on said bracket is an operating arm or lever 137, one end of which engages the valve plunger 132 while the other end is connected by the spring 138 to the hand lever 139 loosely mounted on shaft 121. Lever 139 has pivoted thereto a spring pressed dog 140 which is adapted to engage a toothed curved rack 141 rigid on the shaft 121. It will be seen from this construction that by varying the position of lever 139 the tension of spring 138 may be regulated to open the valve 131 at different points in the movement of arm 122 on this shaft.

A pair of levers 142 are pivotally mounted at 143 on the forward ends of the respective brackets 119, the forward end of each lever being provided with a relatively narrow and extended clamping jaw 144, each jaw having disposed therein a cushion 145 which may be made of rubber or any other suitable material (Figs. 1 and 6). To the opposite ends of the levers 142 links 146 are connected, which links are also pivotally connected to the piston rod 147 carried by the piston 148 of cylinder 149. Leading into the cylinder 149 on opposite sides of the piston are the respective air supply pipes 150 and 151 which communicate with the interior of the valve 152, the latter being similar in all respects to the valves 22 and 107. The valve 152 communicates by means of the pipe 153 with the air tank 134. The valve 152 is actuated by the arm 154 connected to a

link rod 155, the latter being also connected to the foot lever 127. In order to prevent too great a clamping action by the jaws 144 and consequent injury to the boot, an adjustable stop screw 156 is provided which limits the forward movement of piston rod 147.

In operation a boot is disposed between the clamping jaws 81 and the opening in the projecting rear portion of the boot tree is disposed over the tapered air supply nozzle 50. This opening is the opening through which air is exhausted from the boot and tree during the curing operation. By reason of the mountings previously described the nozzle 50 may be readily adjusted for different sizes and styles of boots. The operator then presses down on pedal 40, and the timing of the various valves is so arranged that the valve 22 is first opened to admit air above the piston 7 in cylinder 5 and thereby close the clamping jaws 10 and 18 on the projecting portion of the boot tree. In the continued downward movement of the foot lever 40 the valve 61 is next actuated to admit air to the interior of the tree and boot. As the boot tree in cross section is of an oval or elliptical form, when the air enters between the tree and boot, it tends first to separate the boot from the tree along the long side of said oval, that is, along the side portions of the boot leg opposite the clamps 81. As the foot pedal 40 is further pressed down the valve 107 opens, which actuates the piston in cylinder 102 and moves forwardly the upper end of lever 96, thereby closing the clamps 81 on the sides of the boot leg and again bringing the sides of the boot leg into contact with the tree. As the air is still escaping between the tree and boot it then passes between those portions of the boot and tree at the short sides of the oval which correspond to the front and back of the boot leg. Hence, it will be seen that the sides of the boot leg are those first freed from adhesion to the boot tree and that upon engagement of the sides by the clamps 81 the front and back of the boot leg are then freed from the tree. In the continued forward movement of lever 96 the entire carriage 73 and supported parts next move to the left in Figure 4 against the resistance of the detent 109, and as the boot tree is rigidly held by the jaws 10 and 18 the boot is drawn off of the tree. In the case of boot trees in which the toe section is permanently connected to the leg section the entire tree is of course withdrawn. As before stated sectional boot trees are in common use, however, in which a leg section is slidably united with a toe section, and in the case of such trees the leg section only is withdrawn from the boot in the operation just described. To remove the toe section the boot 157 is then placed on the rest 118

in the position shown in Figure 6 with the boot leg embracing the closure 129. The foot lever 127 is then pressed down, and the parts are so timed that in the downward movement of the lever 127 the valve 152 is first actuated to admit air in rear of the piston 148, which causes the clamping jaws 144 to close on the boot leg over the closure 129 thereby sealing the open end of the boot leg. 5 In the further downward movement of the foot lever 127 the valve 131 is next opened to admit air through the pipe 130 to the interior of the boot, and following this the arm 122 has moved downwardly far enough 10 to engage the flexing rollers 123 and 124 with the top and bottom of the toe portion of the boot. This flexing action of the rollers 123 and 124 releases the toe section of the tree allowing it to drop, and upon release 15 of the foot lever 127, the toe section may then be shaken or drawn out of the boot leg. 20

While a specific embodiment of the invention adapted for the removal of boot trees from boots has been shown and described, it is obvious that the device may be applied to the removal of other forms from rubber articles and that numerous changes may be made in the details. 25

It will be seen that by my invention a machine has been provided for the automatic withdrawal of a form from vulcanized articles such as boots, that the time and manual labor formerly required have been obviated, and that the danger of injury to the article 30 while removing it from the form has been practically done away with.

Numerous modifications will suggest themselves to those skilled in the art, and it is not desired to limit the invention other 35 than as set forth in the appended claims.

Having thus described my invention what I claim and desire to protect by Letters Patent is:—

1. A machine for removing a soft rubber vulcanized article from the form on which it is cured, comprising means for breaking the adhesion between the article and form, means for withdrawing one of them from the other by a relative bodily movement, and 45 means for successively actuating said first two means.

2. A machine for removing a soft rubber vulcanized article from the form on which it is cured, comprising means for breaking the adhesion between the article and the form, means for withdrawing the article by a bodily movement while the form is held 55 stationary, and means for successively actuating said first two means.

3. A machine for removing a soft rubber vulcanized article from the form on which it is cured, comprising fluid pressure means for breaking the adhesion between the article and the form, means for withdrawing 60 one of them from the other by a relative

bodily movement, and means for successively actuating said first two means.

4. A machine for removing a soft rubber vulcanized article from the form on which it is cured, comprising fluid pressure means 70 for breaking the adhesion between the article and the form, means for withdrawing the article from the form by a relative bodily movement, and means for successively actuating said first two means. 75

5. A machine for removing a footwear article from the form on which it is cured, comprising fluid pressure means for successively breaking the adhesion between the article and form at different points, and 80 means for moving one of them relatively to the other. 85

6. A machine for removing a footwear article from the form on which it is cured, comprising fluid pressure means for successively breaking the adhesion between the article and form at different points, and means for withdrawing the article from the form. 90

7. A machine for removing a footwear article from the form on which it is cured, 95 comprising means for admitting fluid under pressure between the article and form, means for insuring the passage of the fluid between the article and form at all points, and means including said last means for withdrawing one of said parts from the other after the adhesion is broken. 100

8. A machine for removing a footwear article from the form on which it is cured, 105 comprising means for admitting fluid under pressure between the article and form, means for insuring the passage of the fluid between the article and form at all points, and means including said last means for withdrawing the article from the form. 110

9. A machine for removing footwear articles from trees, comprising means for clamping the tree, means whereby a supply of pressure fluid may be introduced between the tree and article, means for clamping the article, and means actuatable by the operator for successively putting into operation said parts and for finally separating the article 115 from the tree. 120

10. A machine for removing footwear articles from trees, comprising means for breaking the adhesion between the article and tree, means for withdrawing the article from the tree by a bodily movement, and means actuatable by the operator for successively putting into operation said means. 125

11. A machine for removing footwear articles from trees comprising controlling means, and means connected thereto for successively clamping the tree, breaking the adhesion between the tree and article, clamping the article, and withdrawing the article from the tree. 130

12. In a machine for removing boots from

- hollow boot trees, tree clamping means, means for introducing pressure fluid between the tree and boot leg, means for insuring the introduction of said fluid to all 5 points between the tree and boot leg, and means including said last means for clamping the boot and withdrawing it from the tree.
13. A machine for removing a footwear 10 article from the form on which it is cured, comprising pneumatic means for partly breaking the adhesion between the article and the form on opposite sides of the leg portion, means for subsequently clamping to 15 the form the sides of the leg portion thus released to thereby cause the adhesion to be broken between the remainder of the leg portion and the form, and means for finally separating the article from the form.
14. A machine for removing a footwear 20 article from the form on which it is cured, comprising means for admitting a gaseous fluid in successive stages between the form and article at all points, and means for 25 separating the form and article.
15. A machine for removing footwear 30 articles from trees, comprising means for admitting pressure fluid to a tree and through the latter between the article and tree, means for clamping the tree, means for 35 clamping the article, and means for causing a relative movement of said last two means.
16. A machine for removing boots from 40 boot trees, comprising means for admitting a gaseous fluid through the tree between the latter and part of the leg portion of the boot, means for then directing the fluid between the tree and the remainder of the leg portion, and means including said last 45 means for drawing apart the boot and tree.
17. A machine for removing boots from 50 sectional boot trees, comprising means for admitting a gaseous fluid through the tree between part of its periphery and the boot, means for then directing the fluid between the remainder of the tree periphery and the boot, means including said last means for drawing apart the boot and leg section of the tree, and means for dislodging the toe portion of the tree.
18. A machine for removing sectional 55 boot trees from boots, comprising means for breaking the adhesion between the leg section of the tree and the boot and withdrawing one from the other, and means for subsequently breaking the adhesion between the boot and the toe section of the tree and flexing the toe of the boot.
19. A machine for separating sectional 60 boot trees from boots, comprising means for removing the leg section of the tree from the boot, and means for removing the toe section of the tree including means for gripping and inflating the boot and flexing its 65 toe portion.
20. A machine for separating sectional boot trees from boots, comprising means for removing the leg section of the tree from the boot, and means for removing the toe section including means for flexing 70 the toe portion of the boot and introducing fluid under pressure between said toe portion and the toe section of the tree.
21. In a machine for removing sectional 75 boot trees from boots, mechanism for removing the toe section including, means for gripping the boot and sealing its open end, means for introducing fluid under pressure to the boot, means for flexing the toe portion of the boot, and controlling means for 80 successively putting into operation said previously recited means.
22. In a machine for removing boots from 85 sectional boot trees, means for removing the toe section of the tree comprising a rest for the heel portion of the boot, means for closing and inflating the boot, and means for flexing the boot toe.
23. In a machine for removing boots from 90 sectional boot trees, means for removing the toe section of the tree comprising a rest for the heel portion of the boot, a closure for the interior of the boot leg, means for clamping the boot leg around said closure, means for inflating the boot, and means for 95 flexing the boot toe on opposite sides.
24. In a machine for removing boots from 100 sectional boot trees, means for removing the toe section of the tree comprising means for closing and inflating the boot, exterior means for dislodging the toe section, and means for successively operating said means.
25. In a machine for removing boots from 105 sectional boot trees, means for removing the toe section of the tree comprising a rest for the heel portion of the boot, a closure for the interior of the boot leg, a pair of clamps for exteriorly gripping the boot leg to clamp it around said closure, means for inflating the boot, and opposed rollers for 110 flexing the top and bottom of the toe portion of the boot.
26. In a machine for removing boots from 115 sectional boot trees, means for removing the toe section of the tree comprising a rest for the heel portion of the boot, a narrow elongated closure for the interior of the boot leg, a pair of elongated clamps for exteriorly gripping the boot leg to clamp it around said closure, means for supplying fluid 120 under pressure through said closure, opposed rollers for flexing the top and bottom of the toe portion of the boot, and means for successively operating said clamps, supplying fluid under pressure and operating said rollers.
27. In a machine for removing boot trees 125 from boots, clamping means for the protruding portion of the tree, means for breaking 130 the adhesion between the tree and the

boot, boot clamping means movable transversely of the boot to clamp the same and also movable in a direction longitudinally of the tree, and means for successively imparting said movements to the boot clamping means.

28. In a machine for removing trees from footwear articles, relatively fixed tree clamping means, means for breaking the adhesion between said tree and the article, article clamping means movable with respect to said first named clamping means, and means for operating said previously recited parts in succession.

15 29. In a machine for removing boots from boot trees, tree clamping means, boot inflating means, boot clamping means having a transverse boot clamping movement and a longitudinal boot withdrawing movement, and means for successively actuating said parts.

30. In a machine for removing boots from boot trees, tree clamping means, boot inflating means, boot clamping means having a transverse boot clamping movement and a longitudinal boot withdrawing movement, unitary means for imparting both said movements to the boot clamping means, means for causing said movements to take place successively, and means for success-

sively operating the tree clamping, boot inflating and boot clamping means.

31. In a machine for removing boots from boot trees, tree clamping means, boot inflating means, a carriage movable longitudinally of the clamped tree, means for yieldingly resisting such longitudinal movement, transversely movable boot clamping means mounted on said carriage, and means connected to the carriage for moving said boot clamping means and also moving the carriage.

32. In a machine for removing boots from boot trees, a resiliently mounted nozzle for engagement with the projecting end of a boot tree, means for supplying fluid under pressure thereto, a pair of clamps for gripping said end and fixedly holding the tree, fluid operated means for moving said clamps, a pair of clamps for gripping the exterior of the boot leg, a movable carriage for said clamps, fluid operated means for successively moving said last named clamps and carriage, and manually operated means for governing the supply of fluid to said parts.

Signed at Seattle, county of King, and State of Washington, this 15th day of November, 1922.

CHESTER J. RANDALL.
